UNITED STATES PATENT OFFICE.

MAURITS J. SANDIN, OF WILKINSBURG, PENNSYLVANIA, ASSIGNOR TO WESTINGHOUSE ELECTRIC & MANUFACTURING COMPANY, A CORPORATION OF PENNSYLVANIA.

REFILLABLE FUSE.

Application filed January 12, 1920, Serial No. 350,948. Renewed February 2, 1924.

To all whom it may concern:

Be it known that I, MAURITS J. SANDIN, a citizen of the United States, and a resident of Wilkinsburg, in the county of Allegheny and State of Pennsylvania, have invented a new and useful Improvement in Refillable Fuses, of which the following is a specification.

My invention relates to fuses and particularly to refillable cartridge fuses.

One object of my invention is to provide a cartridge fuse that shall permit the escape of gas to prevent damage to the cartridge; that shall so regulate the rate of escape of the gas as to maintain a proper relatively high internal pressure to reduce the arc and that shall so conduct the gas through passages of predetermined cooling area as to prevent the emission of flame.

Another object of my invention is to provide a plurality of members, for disposition adjacent to each end of a refillable cartridge fuse, which are formed and related to provide a gas-cooling chamber or chambers of predetermined surface cooling area for a fuse of a given capacity.

Another object of my invention is to provide a refillable cartridge fuse that shall be effective in operation, economical to manufacture and easy to manipulate.

Reference may be had to copending application, Serial No. 351,000, filed Jan. 12, 1920, by M. J. Sandin and J. B. MacNeill and assigned to the Westinghouse Electric & Manufacturing Co. in which is disclosed a cartridge fuse adapted for substantially the same purpose as my present invention but which is of different operation and construction.

The present standard forms of cartridge fuses and the stationary terminal clips therefor are of certain dimensions and construction for given ratings. These features have resulted from relatively long practice during which the proper proportions, forms and materials have been determined.

The features of preventing the disruption of certain parts and the emission of flame have not, to the best of my knowledge, been developed to such a stage as to ensure all of the characteristics of economy, effectiveness and adaptability for use with cartridge fuses of standard sizes. Further, and irrespective of whether the fuses heretofore employed were of standard or of special construction,

it is not known by me that any of them were designed to have definite predetermined relations between the internal pressure, the rate of escape and the degree of cooling of the gases generated in the cartridge.

In practicing my present invention, I provide a cartridge fuse constructed in accordance with standard requirements in which the internal pressure, rate of gas escape and degree of cooling are of definite predetermined relation and co-operate in such manner as to permit the internal pressure to be of the highest value consistent with the strength of the cartridge to retard the arc. The gas is, also, so cooled as to prevent the emission of flame to the exterior of the cartridge.

Figure 1 of the accompanying drawings is a view, partially in elevation and partially in section, of a renewable cartridge fuse embodying my invention; Fig. 2 is an end view of the same and Figs. 3, 4, 5, 6, 7 and 8 are detail views of various washers embodied in my invention.

The device comprises, in general, an insulating casing 1, end ferrules 2 having inwardly extending flanges 3, terminal blade members 4, washers 5 for positioning the blade members 4 with respect to the casing, washers 6 for supporting the washers 5 on the blade members 4 by means of screws 7, washers 8 co-operating with the washers 6 to provide a gas-escape passage 9 therebetween to clearances between the blade members 4 and the washers 5 and 6, and a fusible element 10 attached to the smaller inner ends 11 of the blade members 4 by bolts 12 and nuts 13 or other means.

The washers 6 and 8 are of such diameter as to be permitted of ready passage through the casing 1 and are rigidly secured to the blade member 4, as by swaging, to provide a firm support for the washer 5.

The washers 5 and 6 have openings or slots 14 and 15, respectively, of predetermined greater transverse area than the cross-section of the blade member 4, at the portion thereof on which they are respectively disposed, to permit the escape of gas at a predetermined rate between the edges of the openings 14 and 15 and the blade member 4. The washer 8 has an opening or slot 16 that conforms to and closely fits the smaller end portion 11 of the blade member 4 to prevent the passage of gas along the blade.

The washer 5 is larger in diameter than the interior diameter of the casing 1, against the end of which it is held by the flanges 3, and has a lug or projecting portion 17 for co-operation with a notch (not shown) in the end of the casing to align the members 4 with each other. The ferrules 2 are preferably threaded to the casing 1.

As shown more clearly in Figs. 7 and 8, the washer 8 is pressed or otherwise formed to provide a relatively shallow channel 18 therein which, when the washers 6 and 8 are mounted in operative position, co-operates with the washer 6 to form the passage 9. The passage 9 has inner walls of relatively-great cooling area, as determined by the capacity of the fuse and the amount of gas generated thereby.

The direct escape of hot gases from the interior of the casing and out along the blade has heretofore been one of the principal objections to certain knife-blade-type cartridge fuses in that, by reason of imperfect fitting and other causes, no definite cooling or control of the rate of escape of the gases has been attempted. In my present device, the gases are directed, from the center of the casing 1, outwardly towards the perimeter of the casing at its ends, through the chambers 9 and through the openings 14 and 15 and along the blade members 4 to the outer air, as above described.

When assembling the terminal parts, the washer 6 is placed over the end 11 against the larger outer end of the blade member 4 and the washer 8 is placed over the end 11 into flat abutment with the washer 6. The edges of the end 11 may be upset, as by a chisel, to provide shoulders 19 for securely holding the washers 6 and 8 in position.

In operation, when the element 10 is volatilized, a quantity of gas, under relatively great pressure, is generated. If the escape passages are too restricted, the force of this gas will explode, or otherwise disrupt portions of, the cartridge. It is, therefore, imperative that the pressure be reduced. On the other hand, a high pressure is desirable to assist in quenching the arc. The mean between these opposing factors lies in having the escape passages of a definite predetermined size for a fuse of given capacity. Also, in a fuse of given capacity, and, therefore, of certain flame-generating property, a definite amount of cooling area must be provided to prevent any flame reaching the exterior of the cartridge. It is not sufficient to merely provide openings to permit the escape of gas. The openings should be in accordance with the explosive force, in which case the arc is held to a minimum at its inception for a fuse of given capacity and a cartridge of given strength.

The area of the cooling surfaces between the washers 6 and 8 is of a predetermined size to cool the flame of the predetermined arc, there being definite relations between internal pressure, rate of escape and the amount of cooling.

While I have shown and described a particular form of my invention, changes may be effected therein without departing from the spirit and scope thereof, as set forth in the appended claims.

I claim as my invention:

1. A refillable cartridge fuse comprising a casing, an end cap member therefor, and a terminal means movable with respect to said casing and said cap member having spaced co-operating surfaces disposed within the casing and providing a gas-cooling chamber therebetween.

2. A refillable cartridge fuse comprising a casing, a terminal member, a washer on the terminal member for positioning the latter with respect to the casing, a second washer on the terminal member for securing said first washer, and a third washer having a surface spaced with respect to said second washer to provide a gas-cooling passage therebetween from the outer edges thereof to an exteriorly-communicating passage adjacent to the terminal member.

3. A refillable cartridge fuse comprising a casing, a terminal-blade member, a washer loosely embracing the blade member for positioning the same with respect to the casing, a washer for securing the positioning washer to the blade member, and a third washer having a surface spaced with respect to said securing washer to provide a gas-cooling passage for directing the gases from the inner perimeter of the casing toward the terminal member and to the exterior of the casing between the blade member and said first and second washers.

4. A cartridge fuse comprising a casing, a terminal member, a transverse washer substantially closing the end of the casing and provided with an opening through which the terminal projects, and means having a passage therein for deflecting and directing the arc gases to the said opening in a direction substantially transverse to the axis of the terminal member.

5. A cartridge fuse comprising a casing, a terminal member, a pair of transverse washers substantially closing the end of the casing, one of the said washers being provided with an opening through which the terminal projects and the other being provided with a groove for directing arc gases between the washers to the said opening.

6. A cartridge fuse comprising a casing, a terminal member and a pair of transverse washer members substantially closing the ends of the casing and having contiguous surfaces, one of the members being provided

- with an opening through which the terminal projects and the contiguous surfaces of the members being formed to provide a channel between them for the passage of arc gases 5 to the said opening.
7. A cartridge fuse comprising a casing, a terminal member, a transverse washer substantially closing the end of the casing and provided with an opening through 10 which the terminal projects, and means for deflecting and directing the arc gases to the said opening in a direction substantially transverse to the axis of the terminal member.
15. 8. A cartridge fuse comprising a casing, a terminal member, a closure member provided with a perforation through which the terminal member projects, and means co-operating therewith to deflect the gases and 20 to conduct them between the closure member and the said means to the said perforation.
9. A cartridge fuse comprising a casing, a terminal member, a closure member provided with an opening adjacent the terminal member, and means on the said terminal member for deflecting the gases within the casing and conducting them between the closure member and the said means to the 30 said opening.
10. A cartridge fuse comprising a casing, a terminal member, a closure member provided with a perforation through which the terminal member projects, and a washer 35 on the terminal member having a passage for conducting gases from a point adjacent the periphery thereof to the said opening.
11. A cartridge fuse comprising a casing, a terminal member, a closure member having a perforation through which the terminal member projects, and a washer on the terminal member having a groove extending from a point adjacent the periphery thereof to the said opening. 40
45. 12. A cartridge fuse comprising a casing, a terminal member, a transverse washer substantially closing the end of the casing, and provided with an opening through which the terminal member projects, and a washer co-operating therewith for preventing the passage of arc gases to the opening except between the said washers, the said washers being constructed to provide a passage for the gases therebetween.
55. 13. A cartridge fuse comprising a casing, a terminal, a closure member having a perforation through which the terminal projects, a gas-deflecting washer on the terminal, means for preventing longitudinal 60 displacement of the deflecting washer with respect to the terminal, and means independent of the terminal for preventing relative movement of the closure member and the deflecting washer along the axis of the terminal. 65
14. A cartridge fuse comprising a casing, a terminal, a pair of washers secured to the terminal and having a gas passage between them leading to an opening in one of the washers through which the terminal projects, and a closure member secured to the casing and having an opening registering with the opening in the said washer, and means for securing the washers to the said closure member. 70
15. A cartridge fuse comprising a casing, a terminal, a pair of washers secured to the terminal, one of them having a perforation through which the terminal projects and the other being provided with a channel 80 forming a gas passage between the washers for establishing communication between the interior of the casing and the said perforation, and a closure member provided with a perforation registering with the perforation in the said washer. 75
16. A cartridge fuse comprising a casing, a terminal, a pair of washers secured to the terminal, one of them having a perforation through which the terminal projects and the other being provided with a channel 90 forming a gas passage between the washers for establishing communication between the interior of the casing and the said perforation, and a closure member provided with a perforation registering with the perforation in the said washer. 95
17. A cartridge fuse comprising a casing, a terminal member, a member for closing the end of the casing and provided with an opening through which the terminal member projects and which permits of the escape of gases between the terminal member and the walls of the opening, and means having a passage therein for deflecting and directing 105 arc gases to the said opening in a direction substantially transverse to the axis of the terminal member. 100
18. A cartridge fuse comprising a casing, a terminal member, a member for closing the end of the casing having means thereon for positioning the member with respect to the casing and provided with an opening through which the terminal member projects, and means having a passage therein 115 for deflecting and directing arc gases to the said opening in a direction substantially transverse to the axis of the terminal member. 110
19. A cartridge fuse comprising a casing, a terminal member, a member for closing the end of the casing provided with a perforation through which the terminal member projects, means co-operating therewith to deflect the gases and to conduct them between the closure member and the said means to the said perforation and means for positioning the said member with respect to the casing. 125
20. A cartridge fuse comprising a casing, 130

1,002,884

a pair of terminal members, a fusible element for connecting the terminal members, closure members of greater diameter than the interior of the casing for closing the ends of the casing, each provided with a perforation through which the terminals project and a gas deflecting member on each terminal member of less diameter than the interior of the casing and which may be passed therethrough having means for conducting arc gases to the said perforation in the closure member. 10

In testimony whereof, I have hereunto subscribed my name this 31st day of December, 1919.

MAURITS J. SANDIN.
